Attorney.

UNITED STATES PATENT OFFICE.

GEBHARD C. BOHN, OF ST. PAUL, MINNESOTA.

REFRIGERATOR-DOOR.

1,263,843.

Specification of Letters Patent. Patented Apr. 23, 1918.

Application filed September 4, 1917. Serial No. 189,484.

To all whom it may concern:

Be it known that I, GEBHARD C. BOHN, a citizen of the United States, residing at St. Paul, in the county of Ramsey and State of Minnesota, 1340 University avenue, St. Paul, Minnesota, have invented certain new and useful Improvements in Refrigerator-Doors, of which the following is a specification.

10 My invention relates to improvements in doors and more particularly to those doors adapted for use on refrigerators where the entire outside is of vitreous material, its object being to provide means for fastening 15 the outer enameled sheathing to the inner portion of the door without running screws or other fastening means through the sheathing.

In the accompanying drawings forming 20 part of this specification

Figure 1 is a section through my improved door;

Fig. 2 is a plan view as taken on line 2—2 of Fig. 1;

25 Fig. 3 is a section taken on line 3—3 of Fig. 2; and

Fig. 4 is a detail view illustrating a modified construction.

Referring to the drawings, A represents 30 a refrigerator door and 2 an enameled plate forming an exterior covering or sheathing for the door. The door is preferably covered upon its inner side with an enameled lining plate 3. The frame work 4, preferably of wood, is constructed in any desired manner 35 and preferably has the usual insulating layers 5 between the outer and inner plates 2 and 3.

In order to support the outer covering 40 plate 2 upon the frame work without running screws or other securing means through the plate, I provide a plurality of strips 6 with mitered corners so that they may be fitted together, as shown in Fig. 2, and form 45 a backing for the outer sheathing plate 2. The outer sheathing plate is held locked upon the strips 6 through the medium of ribs or flanges 7 extending longitudinally along the outer edges of said strips, the 50 free edges 8 of the plate 2 extending upwardly and inwardly whereby to fit over said flanges 7, as illustrated best in Fig. 1.

In order that the strips 6 may be placed

in position interlocking with the edges of the sheathing 2, I may cut one of the strips 55 into two members with overlapping ends 9 and 10. It is obvious that if all the strips 6 were constructed with a flange which would fit under the inturned edge of the sheathing, it would be impossible to get all 60 the strips in the position shown and in order to overcome this difficulty, I either leave the flange off of one member of the sectional strip or, as shown in Fig. 3, make the flange 65 small enough so as not to cause difficulty in the assembling of the parts.

I may, however, cut one of the strips into three sections, as illustrated in Fig. 4, and where I do this, I am able to form the outer edges of all of the strip sections with a full 70 sized flange 7. In utilizing the form of strip, shown in Fig. 4, the two ends may be shoved endwise into position and the central pieces then shoved in between the ends.

When the strips are thus fitted to the back 75 of the sheathing plate 2, the frame work will be placed thereon and secured thereto, as shown in Fig. 1. This will hold the strips in position interlocking with the edge of the sheathing plate. It is thus impossible 80 to separate the sheathing plate from the door when the parts are assembled and the frame work secured to the strips 6. With the frame work disconnected from the strips 6, the strips are easily forced into locking 85 engagement with the edge of the sheathing plate or out of engagement therewith. I thus by the features of construction shown 90 secure a sheet metal covered door, which, by reason of needing no screws or other means passing through the sheathing to hold it in place, will give a smooth exterior finish and make the construction particularly sanitary.

I claim:

1. A door construction including an exterior sheathing plate, a sectional backing portion interlocking with the edges of said plate and an inner door portion secured to said back portion and holding the same in locking engagement with the plate. 95

2. A door of the class described including a metal covering plate formed with inturned edges, backing strips interlocking with said edges and an inner door portion secured to said strips and holding the same in locking 105 engagement with said plate.

3. A door of the class described including an outer covering plate formed with in-turned edges, backing strips formed with flanges fitted under said edges and an inner door portion secured to said backing strips and holding the same in normal position for the purpose set forth.

In testimony whereof I affix my signature in presence of two witnesses.

GEBHARD C. BOHN.
